(57) **CLAIM**

The ornamental design for a toothpaste tube holder, as shown and described.

DESCRIPTION

FIG. 1 is a perspective view of a toothpaste tube holder in full lines with a tube of toothpaste shown in broken lines representing environmental association matter being for illustrative purposes only and forming no part of the claimed invention.

FIG. 2 is a front elevational view of the toothpaste holder.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.
